Primary Examiner — Brett Miller(74) *Attorney, Agent, or Firm* — Lee & Hayes, P.C.(57) **CLAIM**

The ornamental design for a toilet building, as shown and described.

DESCRIPTION

FIG. 1 is a front, top perspective view of a toilet building;
FIG. 2 is a front view thereof;
FIG. 3 is a back view thereof;
FIG. 4 is a left-side view thereof;
FIG. 5 is a right-side view thereof;
FIG. 6 is a top view thereof; and,
FIG. 7 is a bottom view thereof.

The dashed broken lines depict portions of the toilet building that form no part of the claimed design. The dot-dashed broken lines represent boundaries of the claimed toilet building and form no part of the claimed design.

1 Claim, 7 Drawing Sheets(56)
